MAGNETIC FOCUSsing DEVICE FOR AN ELECTRON TUBE

Ryuzo Orui, Minato-ku, Tokyo, Japan, assignor to Nippon Electric Company, Limited, Tokyo, Japan, a corporation of Japan

Filed Jan. 8, 1962, Ser. No. 164,752

Claims priority, application Japan, Jan. 19, 1961,

4 Claims. (Cl. 315—3.5)

This invention relates to a magnetic focussing device for a long electron beam such as may be found in a travelling-wave tube; and more particularly to a magnetic focussing device of the so-called immersed-field type which is composed of a combination of a uniform and a periodic magnetic focussing device.

In a travelling-wave tube immersed-field type beam focussing, wherein not only the helical slow-wave circuit but also the electron gun are immersed in the magnetic field, is used in order to reduce noise. Previous focussing of this type has employed a uniform magnetic focussing device which covers the whole length of the travelling-wave tube. Where this includes the electron gun portion of the tube the device becomes too bulky and heavy.

In order to reduce the dimensions and weight of the focussing device, it is desirable to employ both uniform magnetic focussing for the electron gun and periodic magnetic focussing for the helical slow-wave circuit. In this combination of uniform and periodic magnetic focussing devices, however, the periodic magnetic field is disturbed by the uniform magnetic field at the portion where they join with the result that the electron beam cannot be sufficiently focussed. Though it would be possible to reduce this disturbance by magnetically shielding the whole outer periphery of the periodic magnetic focussing device, the result would be a reduction in the focussing magnetic field because of the leakage circuit formed at the outside of the travelling-wave tube by the shielding means itself. Furthermore, such shielding means will produce difficulties in focussing the electron beam in a straight pattern, due to the non-alignment of the axes of the magnetic focussing device and the shielding means.

Hence the object of the invention is to provide a magnetic focussing device for an electron tube whose electron beam is focussed by means of an immersed-field, which is light in weight yet avoids detrimental field interferences and provides good beam focussing.

The above-mentioned and other features and objects of this invention and the manner of attaining them will become more apparent and the invention itself will be best understood by reference to the following description of several embodiments of the invention taken in conjunction with the accompanying drawings, in which:

FIG. 1(a) shows schematically an axial section of a travelling-wave tube having both uniform and periodic magnetic field devices, and employing the so-called immersed-field type beam focussing.

FIG. 1(b) illustrates graphically the magnetic field effects along the axis of the travelling-wave tube.

FIG. 2(a) shows a somewhat more detailed axial section of the uniform magnetic focussing device 11 of FIG. 1(a).

FIG. 2(b) illustrates graphically the magnetic field along the axis of the uniform magnetic focussing device of FIG. 2(a).

FIG. 3(a) shows an axial section of a periodic focusing device according to the present invention.

2

FIGS. 3(b) and 3(c) illustrate graphically the magnetic field distribution of the device of FIG. 3(a).

FIG. 4 shows an alternative embodiment of the invention.

FIGS. 5 to 9 show modifications of the permanent magnetic elements used in the invention.

Referring to FIG. 1(a) which shows schematically an axial section of a travelling-wave tube 10 with an immersed-field type magnetic focussing device; a uniform magnetic focussing device 11 is disposed around an electron gun 13 contained within a glass envelope 12 of the travelling-wave tube, while a periodic magnetic focussing device 14 is disposed around the helix 15 thereof.

The uniform magnetic focussing device itself is, as shown in FIG. 2(a), composed of a cylindrical permanent magnet 17 with thin annular magnetic pole pieces 18 and 19 contiguous to both ends. Although in the drawing the cylindrical magnet 17 is shown as a single permanent magnet for the sake of simplicity, it may include a plurality of serially piled thin annular permanent magnets. The axial distribution of the magnetic field produced by this device is shown by curve 20 of FIG. 2(b) wherein the ordinate represents the magnitude of the magnetic field (the positive part of the ordinate corresponding to a right hand directed magnetic field) and the abscissa the distance along the axis. As is evident from this drawing, the leakage flux produces, at the outside portions adjacent the poles of the magnetic device 11, counter magnetic fields (denoted by 21 and 22) whose field strengths are of the order of H_m' as compared with that of the positive magnetic field H_m .

Returning to FIG. 1(a) the periodic permanent focusing device 14 produces a periodical distribution of the magnetic field along the axis as shown by a dotted curve 25 in FIG. 1(b). Here again the ordinate represents the magnitude of the magnetic field (the positive part of the ordinate corresponding to the righthand directed magnetic field), and the abscissa represents the distance along the axis. It is assumed that at the line X—X between the uniform magnetic focussing device 11 and the periodic magnetic focussing device 14, one pole of the former faces the same pole of the latter and that in the righthand side of the line X—X the poles of the cylindrical magnets, constituting the periodic magnetic focussing device 14, face poles of like polarity.

When the two focussing devices are used in conjunction with one another as shown in FIG. 1(a), the dotted curve 25 representing the periodic device and the dot-dash curve 22 representing the uniform device are superposed as shown in FIG. 1(b). The resultant magnetic field is denoted by 26. As will be evident from the foregoing, the simple combination of the uniform and the periodic focussing devices cannot satisfactorily focus an electron beam. The present invention intends to make the resultant magnetic field 26 nearly sinusoidal by varying the field distribution along the axis so as to cancel the effect of the leakage magnetic field 22.

In FIG. 3(a), which shows an embodiment of the invention, both the travelling-wave tube within the magnetic focussing device and the uniform magnetic focussing device at the lefthand side of the line X—X are omitted since they are identical to the corresponding portions shown in FIG. 1(a). The elements constituting the periodic magnetic focussing device 14 are permanent magnets 31, 32, 33, . . . and pole pieces 41, 42, 43 . . . interposed between the uniform focussing device 11 and the periodic focussing device 14 as well as between the magnets 31, 32, 33, ... The magnitude of the magnetic field at middle points A, B, C, . . . of the respective magnets 31, 32, 33, . . . will now be considered. At points A, C, E, . . . the periodic magnetic fields 51, 53, 55, . . .

(produced by the cylindrical magnets 31, 33, 35, . . .) are of the same sense as the leakage magnetic field 22 originating from the uniform focussing device 11; hence the magnetic fields produced by these magnets may be of rather weak intensity. The periodic magnetic fields 52, 54, 56, . . . (produced by the cylindrical magnets 32, 34, 36 . . .) at the points B, D, F, . . . on the other hand are of the reversed sense to the leakage magnetic field 22, and therefore, the magnetic fields produced by these magnets must be sufficiently large to surmount the leakage magnetic field. Where cylindrical magnets 31, 32, 33, . . . are designed to have equal magneto-motive force, the lengths of the axially extending portions of the pole pieces 41, 42, 43 . . . are properly adjusted to vary the magnetic resistances and thus the magnetic fields at the points A, B, C, . . . More particularly, the axial lengths of extended portions 61, 63, 65, . . . at the innermost portion of the pole pieces 41, 42, 43, . . . are made small so as to decrease the magnetic field along the axis at the middle points A, C, E, . . . Inasmuch as the influence of the leakage magnetic field decreases with the order of the middle points A, C, E, . . ., the lengths of the extended portions 61, 63, 65, . . . are increased in this order. Similarly, the lengths of the extended portions 62, 64, 66, . . . are reduced with the order of the middle points B, D, F, . . . In this way quasi-periodic magnetic field 50 (defined by $F_2(x)$ where F_2 is a function of x , the axial distance from line X—X) having a varying amplitude as shown in FIG. 3(b) is obtained, which, when superposed on the leakage magnetic field 22 (defined as $F_1(x)$ where F_1 is another function of x) results in a periodic magnetic field 60 of constant amplitude as shown in FIG. 3(c). Although the pole pieces are shown to vary in width at the inner diameter they may similarly be varied at the outer diameter with the same effect.

FIG. 4 shows another embodiment of the invention wherein the size and thus the magnetic magnitude of the cylindrical magnets themselves is varied. Here, as may be seen, magnets 62, 64, 66, . . . are of increasing intensity and size while magnets 61, 63, 65, . . . are of decreasing intensity and size, so as to cause field distribution equivalent to that obtained by the embodiment of FIG. 3(a). Naturally in this embodiment, the pole pieces, while being constant in their axial extensions, vary radially to conform with the size of the magnet.

Instead of varying the size of the magnets the material of which they are composed may also be varied so as to vary the field intensity or remanence exhibited by each. Also, although the embodiment of FIG. 4 shows a constant inner diameter, the outer diameter of the cylindrical magnets may remain fixed while the inner diameters are varied.

Means for coupling into or out of the traveling wave tube may be inserted in the conventional manner without detracting from the invention. Yasuda's Patent No. 2,991,382 is illustrative. Since the requirement of the periodic magnetic field at magnets 31, 33 is small such coupling means are preferably inserted there.

In the above described embodiments only cylindrical magnets are shown. These permanent magnets, however, need not necessarily be cylindrical, but may be plate or bar magnets. FIGS. 5, 6 and 7 show a modification wherein plate magnets are used. A uniform magnetic device or an element of a periodic magnetic device is formed by disposing two plate magnets 71 and 72 above and below the tube 73 and attaching rectangular pole pieces 74, having a central circular bore such as shown in FIG. 7, to the pole portions of the magnets. Further magnets 75 and 76 may also be added as shown in FIG. 8. Alternatively, as shown in FIG. 9 several bar magnets 77 may be disposed around the tube 73 on a cylindrical surface whose center coincides with the tube axis.

While I have described above the principles of my invention in connection with specific apparatus, it is to be clearly understood that this description is made only by

way of example and not as a limitation to the scope of my invention, as set forth in the objects thereof and in the accompanying claims.

What is claimed is:

1. A magnetic focussing system for a travelling wave tube including an electron gun region and a delay line region comprising:

a uniform magnetic device for producing a substantially uniform magnetic field axially threading said electron gun region of an inserted travelling wave tube, said device having an inherent leakage magnetic field;

a periodic magnetic device encircling the delay line region of said tube, having a sequence of successively oppositely directed annular permanent magnets of equal magnetic strength

and radial pole pieces arranged between respective pairs of neighboring of said magnets, each of said pole pieces having an annular axial segment, said segments being of substantially equal length and being fixedly positioned relative to said pole pieces to provide different axial separations between adjacent successive pairs of said axial segments such that the magnetic effect of magnets having magnetic fields opposed to said leakage flux will be increased and the magnetic effect of magnets having magnetic fields in coincidence with said leakage magnetic field will be decreased, the difference in said separation between adjacent successive pairs of segments decreasing with distance from said uniform magnetic device to compensate substantially for the effects of said inherent leakage magnetic field on said periodic magnetic field.

2. A magnetic focussing system for a travelling wave tube including an electron gun region and a delay line region comprising:

a uniform magnetic device for producing a substantially uniform magnetic field axially threading said electron gun region of an inserted travelling wave tube, said device having an inherent leakage magnetic field;

a periodic magnetic device encircling the delay line region of said tube, having a sequence of successively oppositely directed annular permanent magnets, all said permanent magnets being of substantially uniform dimension,

and pole pieces arranged between respective pairs of neighboring said magnets, each of said pole pieces having an annular axial segment,

the axial spacing between said axial segments of said pole pieces being substantially uniform, the magnetic field strengths of successive magnets being of increasing and decreasing magnetic intensity so as to increase the magnetic effect of magnets having fields opposed to said leakage magnetic field and decrease the magnetic effect of magnets having magnetic fields in coincidence with said leakage magnetic field in a decreasing amplitude with distance from said uniform magnetic device, to compensate substantially for the effects of said inherent leakage magnetic field on said periodic magnetic field.

3. A magnetic focussing system for a travelling wave tube including an electron gun region and a delay line region comprising:

a uniform magnetic device for producing a substantially uniform magnetic field axially threading said electron gun region of an inserted travelling wave tube, said device having an inherent leakage magnetic field;

a periodic magnetic device encircling the delay line region of said tube, having a sequence of successively oppositely directed annular permanent magnets;

and pole pieces arranged between respective pairs of neighboring said magnets, each of said pole pieces having an annular axial segment;

the inner and outer diameter of said permanent magnets being varied so as to increase the magnetic effect of magnets having fields opposed to said leakage magnetic field and decrease the magnetic effect of magnets having magnetic fields in coincidence with said leakage magnetic field in a decreasing amplitude with distance from said uniform magnetic device, to compensate substantially for the effects of said inherent leakage magnetic field on said periodic magnetic field.

4. A magnetic focussing system for a travelling wave tube including an electron gun region and a delay line region comprising:

a uniform magnetic device for producing a substantially uniform magnetic field axially threading said electron gun region of an inserted travelling wave tube, said device having an inherent leakage magnetic field;

a periodic magnetic device encircling the delay line region of said tube, having at least two successively oppositely directed bar permanent magnets; and rectangular pole pieces arranged between respective pairs of neighboring said magnets, each of said pole pieces having an annular axial segment;

10

15

20

25

the inner and outer diameters of said bar permanent magnets, and the permanence characteristics of said magnets, located adjacent said uniform magnetic device being proportioned relative to one another to increase the magnetic effect of magnets having fields opposed to said leakage magnetic field and decrease the magnetic effect of magnets having magnetic fields in coincidence with said leakage magnetic field in a decreasing amplitude with distance from said uniform magnetic device, to compensate substantially for the effects of said inherent leakage magnetic field on said periodic magnetic field.
